POWER UNIT FOR MIXING INVESTMENT

Edmund A. Steinbock, Jr., Louisville, Ky., assignor to Whip-Mix Corporation, Inc., Louisville, Ky., a corporation of Kentucky

Filed Nov. 5, 1959, Ser. No. 58,211

Term of patent 14 years

(Cl. D24—1)

Fig. 1.

Fig. 2.

Fig. 5.

Fig. 3.

Fig. 4.

FIG. 1 is a front elevational view of a power unit for mixing investment, showing my new design;

FIG. 2 is a side elevational view thereof;

FIG. 3 is a top plan view thereof;

FIG. 4 is a bottom plan view thereof; and

FIG. 5 is a perspective view thereof in a horizontal position.

The side not shown is substantially like the side shown and the rear bracket not shown is substantially plain and conventional.

I claim:

The ornamental design for a power unit for mixing investment, substantially as shown and described.
